UNITED STATES PATENT OFFICE.

CHARLES F. RICHON, OF NEW YORK, N. Y., ASSIGNOR TO CHENEY BROTHERS, OF SOUTH MANCHESTER, CONNECTICUT, A CORPORATION OF CONNECTICUT.

DESIGN FOR TEXTILE FABRIC.

No. 37,612.

Specification for Design.

Patented Oct. 31, 1905.

Application filed August 22, 1905. Serial No. 275,329. Term of patent 33 years.

To all whom it may concern:

Be it known that I, CHARLES F. RICHON, a citizen of the United States, residing in the borough of Richmond, city of New York, Richmond county, State of New, have invented a new, original, and ornamental Design for Textile Fabrics, of which the following is a specification, reference being had to the accompanying drawing, forming a part thereof.

The figure is a plan view of the fabric, showing my new design.

I claim—

The ornamental design for a textile fabric, as shown.

CHARLES F. RICHON.
